[57] CLAIM

The ornamental design for a combined belt and tennis ball holder, as shown and described.

DESCRIPTION

FIG. 1 is a rear perspective view of a combined belt and tennis ball holder showing my new design;
FIG. 2 is a front perspective view with the ends unfastened; and

FIG. 3 is a bottom perspective view of one of the ball holders, with the belt broken away for convenience of illustration.

FIG. 3

FIG. 2
